(57) **CLAIM**

The ornamental design for a mobile phone, as shown and described.

DESCRIPTION

FIG. 1 is a front perspective view of a mobile phone in a closed position;

FIG. 2 is a front view of the mobile phone of FIG. 1;

FIG. 3 is a rear view of the mobile phone of FIG. 1;

FIG. 4 is a left side view of the mobile phone of FIG. 1;

FIG. 5 is a right side view of the mobile phone of FIG. 1;

FIG. 6 is a top view of the mobile phone of FIG. 1;

FIG. 7 is a bottom view of the mobile phone of FIG. 1; and,

FIG. 8 is a front perspective view of a mobile phone of FIG. 1 in an open position, wherein the outer panel of the front and the two adjacent interior surfaces of the central and rear panels as shown in FIGS. 1-7 are oriented in a planar relationship.

1 Claim, 6 Drawing Sheets
